UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

CUTLET-BOX.

1,007,420.

Specification of Letters Patent. Patented Oct. 31, 1911.

Application filed July 19, 1907. Serial No. 384,520.

To all whom it may concern:

Be it known that I, REUBEN B. BENJAMIN, a citizen of the United States, residing at Chicago, in the county of Cook and State of Illinois, have invented new and useful Improvements in Outlet-Boxes, of which the following is a full, clear, concise, and exact description, reference being had to the accompanying drawing, forming a part of this specification.

My invention relates to outlet boxes such as are employed where it is desired to connect translating devices with conduit-protected electrical conductors, and resides in novel and advantageous features of construction and arrangement, whereby an improved device for the purpose described is obtained.

Outlet boxes of the class to which my invention relates, are for the purpose of protecting the translating devices, such as incandescent lamps, and their associated arrangements against severe weathering, moisture and other destructive conditions, and are of particular utility for use on ship-board, in tunnels and in similar places, where these agencies, which are liable to interfere with the proper operation of the translating devices, are present. In prior art structures, to secure a weather-proof and moisture-proof construction, complex arrangements consisting of many parts, were necessarily employed. My invention however, provides a device which does not have these disadvantages, being constructed of simple and easily assembled parts, and which thoroughly protects the translating devices against destructive extraneous conditions.

The outlet box of my invention is illustrated in the accompanying drawings, in which—

Figure 1 is an elevational view thereof; Fig. 2 is a central longitudinal sectional view on the line 2—2 of Fig. 3, looking in the direction indicated by the arrows; Fig. 3 is a plan view; Fig. 4 is a view of the under side thereof, parts being removed to disclose the construction; Fig. 5 is a sectional view similar to that of Fig. 2, illustrating modifications within the scope of my invention; and Fig. 6 is a similar sectional view illustrating another modification.

The device consists primarily of the cas-

ing 10, of cast iron or other durable material, which is adapted to be placed in the path of the electrical conductors with which it is desired to connect the translating device. These conductors, indicated at 11, 11 in the drawings, are disposed within protecting conduits, which, as shown at 12, 12, may be pipes of iron or other substantial material, which as particularly illustrated in Figs. 1 to 4 inclusive lead into the casing by way of openings with which they have threaded engagement. To insure against abrasive wear of the insulation of the conductors 11, 11, buffers 13, 13 of hard rubber or other suitable material may be advantageously disposed on the inner ends of the conduits 12, 12.

The casing is open at one side and is provided with a cover 14 clamped thereto by means of screws 15, 15 passing through apertures therein and having threaded engagement with the casing, a rubber gasket 16 being disposed between the cover and the casing to effectively exclude moisture from the box. As these devices are, in their ordinary usage, for the purpose of accommodating incandescent lamps, a lamp receptacle 17 is secured to the inner side of the cover 14, in register with the opening 18 therein, by means of screws 19, 19 passing through the cover and engaging in threaded openings in the porcelain casing of the receptacle. The circuit conductors 11, 11 are connected with the terminals of the receptacle 17 as indicated at 20 in the drawings. A suitable glass casing 21 is provided for the protection of the incandescent lamp, and has threaded engagement with a supporting member 22 which has the inwardly extending flange 23, clamped between the cover 14 and the rubber gasket 16. A washer 24 is placed within the supporting member 22 in such a manner as to be clamped securely therein when the glass casing 21 is screwed into the supporting member, thus assisting in securing a thoroughly protective arrangement.

It is usually desirable to employ reflecting means for well known purposes, and I have shown means whereby a reflector may be properly and conveniently accommodated. An annular supporting member 25 is clamped between the heads of the screws 15 and the cover 14 and is provided with an

extending rim flange 26 which is crimped at 27 as indicated in the drawings to accommodate a spring wire 28 to which is secured the reflector 29, suitably disposed relative 5 to the incandescent lamp 30, inserted into the receptacle 17. The spring wire is split at 31 to admit of its ready removal and its adjustment into any desired position so as to most advantageously reflect the light.

10 It frequently occurs, when an outlet box is desired to be connected with the conduit, that the immediate surroundings are such as to prevent free manipulation of the device and of tools to secure the joint between 15 the casing and the conduits illustrated in Figs. 1 to 4. When occasion arises where such a joint would be impracticable the construction shown in Fig. 5 may be employed. In this arrangement the pipe 12 is not 20 threaded into the opening in the casing but is merely disposed proximate thereto, suitable means being provided to hold the same in place and to form a moisture-proof joint. The sleeve 32 is threaded on the pipe 12 and 25 is adapted to be manipulated to firmly clamp the gasket 33 against the face of the annular boss 34 about the opening provided in the casing. The sleeve 32 has a collar 35, and a clamping cap member 36 is threaded on the 30 outside of the boss 34 and engages the collar 35 to clamp the same against the boss, thereby securing an efficient moisture-proof joint. It is evident that the parts are easily manipulated and the joint can be employed even 35 though the position of the outlet box be an inconvenient one.

In Fig. 5 I have also illustrated a modification which provides for the attachment of a shade instead of a globe, for the incandescent lamp. A supporting plate 37 is clamped between the heads of the clamping screws 15, 15 and the cover 14, and is provided with the center opening 38 into which extends the flange portion 39 of the shade holder 40, this flange portion being burred over as indicated at 41 in the drawings to rigidly secure the shade holder to the supporting plate. The shade holder is provided with the thumb screws 42, as is usual

in the art, to retain in place a suitable 50 shade 43.

In Fig. 6 I have shown another modification for accommodating a shade. In the arrangement illustrated in this figure the supporting member 44 is clamped between the 55 cover 14 and the gasket 16. The rim flange of this supporting member is provided with the thumb screws 45 to support the shade in an apparent manner.

I claim as new and desire to secure by Letters Patent:

1. In an outlet box, the combination with a casing, of a cover therefor, a lamp receptacle supported in the casing, and a globe support clamped to the casing with said 65 cover.

2. In an outlet box, the combination with a casing, of a cover therefor, and a globe support and a reflector support clamped with 70 said cover to the casing.

3. In an outlet box, the combination with a casing, of a cover therefor, a globe support and a reflector support clamped with said 75 cover to the casing, and a lamp receptacle secured to said cover.

4. In an outlet box, the combination with a casing, of a cover therefor, a globe support, a reflector support and a screw passing through said reflector support, globe support and cover, and having threaded engagement with said casing.

5. In combination, a casing having openings for the admittance of conductor wires, of a cover for said casing, a lamp receptacle secured to said cover, a globe support 85 clamped to said casing with said cover, a globe supported thereby, a gasket disposed between said globe support and said casing, a reflector support clamped to said cover, and a reflector supported thereby.

In witness whereof, I have hereunto subscribed my name in the presence of two witnesses.

REUBEN B. BENJAMIN.
